US0D1040164S

(12) **United States Design Patent** (10) Patent No.: **US D1,040,164 S**
Venica et al. (45) Date of Patent: ** Aug. 27, 2024

(54) **DATA DISPLAY SCREEN WITH GRAPHICAL USER INTERFACE**

(71) Applicant: **COL-VEN S.A.**, Santa Fe (AR)

(72) Inventors: **Natalio Domingo Venica**, Santa Fe (AR); **Primo Antonio Colussi**, Santa Fe (AR)

(73) Assignee: **COL-VEN S.A.**, Santa Fe (AR)

(**) Term: **15 Years**

(21) Appl. No.: **29/825,865**

(22) Filed: **Feb. 7, 2022**

(30) **Foreign Application Priority Data**

Nov. 25, 2021 (AR) 100824

(51) **LOC (14) Cl.** **14-04**

(52) **U.S. Cl.**

USPC **D14/485**
